UNITED STATES PATENT OFFICE

GEORGE L. VAN ALLEN, OF NEWARK, NEW JERSEY, ASSIGNOR TO BAKER & CO. INC.,
A CORPORATION OF NEW JERSEY

PROCESS AND APPARATUS FOR FORMING METAL PLATES FOR DENTURES

Application filed March 23, 1928. Serial No. 264,096.

The objects of this invention are to secure an improved process of drawing or shaping out of sheet metal the forms which are employed as the bases for building up dentures, either partial or full; to secure more perfect and accurate forms or plates, and to avoid any cracks or splits in the same such as destroy their smooth surface or continuity and have to be laboriously corrected by hand; to expedite and facilitate the formation of such plates, and cheapen as well as improve the production of them, and to obtain other advantages and results as may be brought out by the following description.

15 Referring to the accompanying drawings, in which like characters of reference indicate the same parts throughout the several views,

Fig. 1 is a plan view of a die such as is employed according to my invention;

Fig. 2 is a plan view of a blank of thin sheet metal which is to be formed upon said die;

Fig. 3 is an edge view of said blank;

Fig. 4 is a cross-section of the die with the blank thereon after receiving an impression;

Fig. 5 is a plan view of the same;

Fig. 6 is a plan view of the blank as shown in Figs. 4 and 5 trimmed for the next impression;

30 Fig. 7 shows in cross-section similar to Fig. 4 the blank after another impression;

Fig. 8 is a plan view of the blank after still further trimming;

Fig. 9 shows in cross-section the blank 35 with its middle portion drawn to its final form; and

Fig. 10 shows it after its final trimming and ready for use.

In said drawings, a die 1 is shown having 40 a central portion constituting what is known in the art as a "model", the particular one illustrated being for a full upper denture and having a depressed middle portion 2 corresponding to the roof of the mouth and a surrounding portion 3 corresponding to the gums. It will be understood that a thin sheet-metal blank is desired to be pressed into the exact form of the said "model", includ- 45 ing the outer wall of the part 3, to form a

base upon which a set of artificial teeth can be formed.

By my invention, I carry the material of which the die 1 is formed, from the base of the outer wall 4 of the gum portion 3 outwardly away therefrom a distance and then upward, preferably flaringly as at 5, to substantially the plane of the top of the gum portion 3, and then outward in said plane, as at 6, sufficiently far to give a firm support 55 and hold to the outer marginal portions of the sheet-metal blank when it is laid upon the die. The die as shown comprises an outer ring 7 in which the shaped metal 8 is enclosed, but this is immaterial to the invention; 60 the die essentially comprises the central model surrounded by the groove 9 and raised portion 10 with its supporting top surface 6.

With a die such as described, the thin sheet 70 metal blank 11, as shown in Figs. 2 and 3, is laid upon the top of the die, being substantially of the same shape and size therewith, and then pressure is applied in any common and well-known manner, such as by means of 75 a piece of rubber with a follower back of the same, the die, rubber, and follower being all enclosed in a suitable ring or cylinder of a press. This is common and well-known in the art and is believed to require no further 80 description here. As is also old in the art, the drawing or forming is done in steps, and the disk or plate annealed between the successive steps, and Figs. 4 and 5 show the completion 85 of the first step. It will be noted that marginal portions 12 of the sheet metal blank are supported upon the top 6 of the outer raised portion 10 of the die, as the forming takes place and progresses, so that the metal is forced downward into the groove 9 outside 90 the gum portion 3 similar to the manner in which it is pressed into the central cavity 2 of the die, and thus as the drawing progresses a marginal portion of the plate lies close 95 against the outer walls 5 of the said groove 9 as well as upon the top 6 of the outer portion of the die, the metal of the plate being swaged downwardly into the groove 9, as at 13, and also into the center hollow portion 2 of the die, as at 14.

The outer raised portion 10 of the die does not shape any portions of the sheet-metal blank for use in the denture, but simply supports or holds them in order to secure a perfect formation of the sheet metal against the outer walls of the gum portion 3 of the die. Therefore, as the outer portion of the blank is extended further down into the groove 9 and particularly in contact with its outer wall, as at 15, Fig. 4, the peripheral marginal portion of the disk can in practice be trimmed away and dispensed with. For example, in Fig. 6, 17 indicates the blank 16 as it is shown in Figs. 4 and 5, after it has been trimmed peripherally, so that it does not overlap quite so far upon the top supporting surface 6 of the die; 18 in Fig. 7 indicates the blank after it has received another impression, and 19 in Fig. 8 shows it still further trimmed so that it has practically no horizontal portion at all to overlie upon the top 6 of the outer raised portion of the die. 20 in Fig. 9 indicates the blank after still another pressure in the die which practically conforms it thereto, and after this the outer marginal portion 21 is trimmed off entirely to the line of the base of the gum, and the plate assumes its final form indicated by 22 in Fig. 10.

It will be understood that the trimming can be done because the outer peripheral portion of the blank still bears against the outer wall 5 of the groove 9 of the die and is sufficiently supported thereby; the trimming must be done in accordance with the support needed by said peripheral portion of the blank, and at no time extend inward too far to remove such support. Otherwise it can be varied in detail by the operator, and of course the number of impressions that the blank receives in the die is immaterial.

While I have shown the blank 11 as a disk or circular, obviously it is not restricted to that shape. Furthermore, while I have illustrated the invention in the production of a plate for a full upper denture, it is just as applicable to the production of plates for full lower dentures or for partial dentures either upper or lower.

Various modifications can be made in carrying out the invention, by those skilled in the art, without departing from the spirit and scope thereof; and therefore I do not desire to be understood as limiting myself except as required by the following claims when construed in the light of the prior art.

Having thus described the invention, what I claim is:

1. A process of forming metal plates for dentures, consisting in supporting a blank at its peripheral marginal portion and indenting its central portion onto a model and into an annular groove between said model and peripheral marginal portion by successive impressions, and trimming away the

peripheral portion of said blank progressively as it conforms to and rests upon the outer wall of the said groove.

2. A die for forming metal plates for dentures, comprising an outer peripheral top portion, a central sunken model portion, and an annular groove between said peripheral top portion and central sunken model portion.

3. A die for forming metal plates for dentures, comprising an outer peripheral top portion, a central sunken model portion, and an annular groove between said peripheral top portion and central model portion, the outer wall of said groove flaring upwardly outward.

4. A process of forming metal plates for dentures, consisting in supporting a blank at its peripheral marginal portion outside a model, indenting its central portion onto the model and into an annular groove between said model and peripheral marginal portion, and trimming away all of the blank outside said model.

5. A process of forming metal plates for dentures, consisting in supporting a blank at its peripheral marginal portion outside a model, indenting its central portion onto the model and into an annular groove between said model and peripheral marginal portion by successive impressions, and peripherally trimming the blank progressively with said impressions.

6. A process of forming metal plates for dentures, consisting in supporting a blank at its peripheral marginal portion outside a model, indenting its central portion onto the model and into an annular groove between said model and peripheral marginal portion by successive impressions, and peripherally trimming the blank progressively as it conforms to the said groove.
